DESIGN.

A. L. HALLIDAY.

CARPET.

No. 15,457.

Patented Oct. 14, 1884.

UNITED STATES PATENT OFFICE.

ARTHUR L. HALLIDAY, OF NEW YORK, N. Y.; ASSIGNOR TO THE BIGELOW CARPET COMPANY, OF CLINTON, MASSACHUSETTS.

DESIGN FOR A CARPET.

SPECIFICATION forming part of Design No. 15,457, dated October 14, 1884.

Application filed August 7, 1884. Term of patent 3½ years.

To all whom it may concern:

Be it known that I, ARTHUR L. HALLIDAY, of New York, county and State of New York, have invented and produced by my own industry, genius, efforts, and expense a new and original Design for a Carpet, of which the following is a correct description, reference being had to the annexed photograph, which represents a face view of my new carpet.

10 This invention relates to a new ornamentation of a carpet, oil-cloth, or similar fabric; and it consists of the novel grouping and outlines of figures hereinafter described.

In the accompanying photograph are represented sundry fanciful figures, A, B, C, D, which are similar to one another in outline, grouped between series of rosettes E, F, G, H, I, J, and K. Near the figures D and H is a fanciful figure, L, and between the figures D

and K is a fanciful figure, M. Beneath the figure K is a group of rosettes, N, O, P, Q, R, S, and T, which embraces figures U, U, that resemble the figures A, B, C, D. The fanciful figure V is placed between the figures N and T. The group of oval rosettes W is placed between the figures M and N. The spaces between the figures mentioned are filled with smaller figures, as shown.

I claim—

The design for carpet or other fabric, the same consisting of figures A, B, C, D, E, F, G, H, I, J, K, L, M, N, O, P, Q, R, S, T, U, V, W, substantially as shown.

ARTHUR L. HALLIDAY.
